UNITED STATES PATENT OFFICE

93,043

DESIGN FOR A TOOTHBRUSH

Frederic A. Parkhurst, Bethesda, Md., and William S. Elliot, Northampton, Mass., assignors to Pro-Phy-Lac-Tic Brush Company, Northampton, Mass., a corporation of Delaware

Application March 2, 1934, Serial No. 50,928

Term of patent 14 years

To all whom it may concern:

Be it known that we, FREDERIC A. PARKHURST and WILLIAM S. ELLIOT, both citizens of the United States of America, residing at Bethesda, county of Montgomery, State of Maryland, and Northampton, county of Hampshire, Commonwealth of Massachusetts, respectively, have invented a new, original, and ornamental Design for a Tooth Brush, of which the following is a specification, reference being had to the accompanying drawing forming a part thereof.

In the drawing:

Fig. 1 is a front elevation of the article showing our new design with the bristles omitted therefrom,

Fig. 2 is a side elevation,

Fig. 3 is a rear elevation,

Fig. 4 is a section along the line 4—4 of Fig. 1, and

Fig. 5 is a section along the line 5—5 of Fig. 1.

The handle becomes gradually thinner toward the rear or free end thereof. In cross section, the handle portion has rounded or convex top and

bottom faces which vary in proportion to the thickness of the handle (see Figs. 2 and 5). The side edges of the handle extend in straight lines and diverge toward the rear end of the handle, which rear end is rounded or convexly curved (see Figs. 1 and 3). The handle converges gradually toward the abbreviated neck portion and then diverges to a point where it joins and merges with the flat side edges of the head portion. The head portion has a gradual outward taper toward its end which is gracefully rounded or convexly curved beyond the forward tuft of bristles, similarly to the rear end of the handle. The under face of the head portion, that is, the face in which the bristles are set, is flat, whereas the opposite or top face of the head portion is slightly curved or rounded transversely to present a graceful convex surface.

We claim:

The ornamental design for a tooth brush substantially as shown and described.

FREDERIC A. PARKHURST.

WILLIAM S. ELLIOT.
